UNITED STATES PATENT OFFICE.

RUDOLF GOLDSCHMIDT, OF BERLIN, GERMANY, ASSIGNOR TO DET TEKNISKE FORSØGSAKTIIESELSKAB, OF CHARLOTTENLUND, DENMARK, A COMPANY OF DENMARK.

MECHANISM FOR CONVERTING ROTARY INTO RECIPROCATORY MOTION.

1,386,329.

Specification of Letters Patent.

Patented Aug. 2, 1921.

Application filed January 10, 1921. Serial No. 436,206.

To all whom it may concern:

Be it known that I, RUDOLF GOLDSCHMIDT, a German citizen, residing at 45, Linden Allee, West End Berlin, Germany, have 5 invented new and useful Improvements in Mechanism for Converting Rotary into Reciprocatory Motion, of which the following is a specification.

This invention relates to mechanism for 10 converting rotary into reciprocatory motion and more particularly for imparting to the reciprocatory member a continued translatory or progressive movement step by step in one direction of the path of reciprocation. 15 This translation or progressive movement may be utilized for example for imparting progressive movement to the reciprocating tup of a drop hammer or the like, thus automatically feeding the tup nearer to the work 20 as required. The translatory or progressive motion may also be utilized in connection with the flapping wings of ornithopters or like flying machines in which the wings, in addition to a flapping or reciprocatory 25 motion, have progressive forward motion in common with the whole flying machine.

According to the present invention, a reciprocatory member, is reciprocated by a rotating centrifugal weight or weights pivoted 30 to the reciprocatory member, and a unidirectional impulse is impressed upon the reciprocatory member at the end of each complete vibration of the member, so that it travels or progresses step-by-step in one 35 direction. This impulse can be impressed upon the member, for example by a buffer which is unidirectionally progressed so that the reciprocatory member is adapted to abut against the buffer before it completes each vibration.

In order that the invention may be more clearly understood reference is hereinafter made to the accompanying drawings, whereon:

Figure 1 is a diagrammatic view of a simple form of the mechanism for straight line motion.

Fig. 2 is a view similar to Fig. 1 showing a slight modification thereof.

50 Fig. 3 is a curve illustrating reciprocatory motion without translation.

Fig. 4 is a curve illustrating progressive or translatory reciprocatory motion obtained by one form of the improved mechanism.

Fig. 5 illustrates diagrammatically the 55 reciprocatory member of Fig. 1 abutting against one of the buffers.

Fig. 6 is a view corresponding to Fig. 5 showing the buffers displaced so as to impart progressive movement to the reciproca- 60 tory member in one direction.

Fig. 7 is a sectional view of the improved mechanism applied to a reciprocatory tool or chisel.

Fig. 8 is a sectional view at right angles 65 to Fig. 7 showing the centrifugal weights and driving gear.

Fig. 9 is a diagram illustrating the reciproca- 70 tory member of Fig. 7 in its end position abutting against the tool.

Fig. 10 is a sectional view of the mechanism applied to a pile-driver or like reciproca- 75 tory tool.

Fig. 11 is a side view, partly in section, of a forging hammer constructed according to 75 the present invention.

Figs. 12 and 13 are diagrammatic views 80 illustrating modified arrangements of the spring or springs on the reciprocatory member.

Fig. 14 illustrates diagrammatically a further modification in which the spring is mounted in the buffer or reciprocated tool itself.

Referring to Fig. 1 of the drawings, the 85 body *a* represents the reciprocatory member which may be the tup of a reciprocated tool or any equivalent reciprocatory element, illustrated as being guided in a straight line by means of guides *f*, *f*. Rotatable about an 90 axis *c* on the body *a* is an arm *s* fitted with a weight *o*.

If the arm *s* is rotated, the resulting centrifugal force *R* accelerates or retards the motion of the body *a* which is set in reciproca- 95 tion by a force *H* equal to *R*.cos. α . If *B* represents the weight of the mass *o*, *l* the distance of the center of the mass *o* from the axis *c*, *A* the weight of the body *a* and *z* the unrestricted travel of the body *a*, then 100

$$z = 2l \frac{B}{A+B}.$$

If *B* were equal to *A*, then *z* would equal *l*. In any case, *z* is quite independent of the 105 angular velocity of the arm *s*, provided that the friction and other power expended is small compared with the change of energy

in the masses. The motion is dependent on the physical law that the center of inertia remains constant, that is to say, no matter what be the position of the centrifugal weight o , the whole system takes up such a position that the center of inertia remains stationary.

In the arrangement according to Fig. 1, wherein only one centrifugal weight o is employed, a disturbing lateral force V is created equal to $R \sin \alpha$. This may be obviated if two equal centrifugal weights o^1 and o^2 are fitted as in Fig. 2 to rotate in opposite directions, the centrifugal forces R_1 and R_2 giving a resultant effective force H .

The arm s may be driven in any desired manner, either by belt or cord drive or by a flexible shaft either wholly flexible or fitted with universal joint at its ends and telescopically movable in the direction of reciprocation. Alternately, the power may be transmitted to the rotary arm s by means of square shafts and gearing slideable thereon or like means, the shaft being disposed 25 parallel to the path of oscillation. Or the arm s may be electrically driven.

The rotating masses have a balancing action on the system, balancing the accelerating and retarding forces of the reciprocating masses and counter-acting any sudden change in velocity.

The foregoing mechanism produces reciprocatory motion as illustrated by the curve in Fig. 3.

The unrestricted travel z of the body a , due to the action of the centrifugal forces of the masses o is dependent on the length of the arm a and the proportions of the masses, and also on the friction and useful work done if these are considerable. The path of reciprocation is thus determined in length z , but its position in space can only be determined by buffers or the like such as d or e . If the distance $d-e$ is somewhat shorter than the unrestricted travel z , the difference may be absorbed resiliently by springs either at d or e or upon the body a . If the buffers d e are adjusted, the position of z will be varied. A very small force will 50 generally suffice to effect this movement. In Fig. 5, the body a is diagrammatically shown in its end position on the left, when it just abuts against the buffer d . If now the buffer d is moved a distance m (Fig. 6) into the position d^1 and the buffer e into the position e^1 while the body a moves between d and e the body a will strike correspondingly earlier against the buffer d^1 at a considerable velocity and will thereby receive, through the 55 springs or by impact, a greater impulse than the body a received at e^1 , the impulse being equal to the force multiplied by the time during which it acts. The increased impulse thus created at the left, will urge the path 60 of reciprocation toward the right until the

body a again assumes a stable path of reciprocation within the new limits d^1 e^1 .

If, however, the oscillating body is not allowed to become stable within the limits d^1 e^1 , but is impressed with a constant impulse in one direction, the system will travel progressively in that direction and produce the reciprocating and progressive movement illustrated by the curve in Fig. 4.

In the case of a vertically reciprocating body, the gravitation of the body will in itself tend to produce progressive movement.

Such progressive reciprocatory motion may be adapted to apparatus whose movement is of a progressive oscillatory character and wherein resistance to movement differs in two succeeding amplitudes of vibration of the apparatus.

In nearly all practical cases, only the progressive component of the compound motion constitutes useful movement. The reciprocating component is in nearly all cases only a kind of auxiliary motion.

Such is the case with a flying machine having flapping wings, wherein the wings move upwardly and downwardly and at the same time have movement in common with the whole flying machine and wherein the air resistance during the down stroke is greater than during the upward movement of the wing.

In the case of a power-driven vertically reciprocated hammer, the impulse due to resistance to movement on the down stroke is also considerably greater and takes place at the end of the stroke on impact. But as, at this moment, the blow is transformed into work, the progressive movement is generally only very slight at the end of each down-stroke, although the force of the blow may be considerable.

In the mechanism described with reference to Figs. 1 to 6 an impulse is impressed upon the reciprocatory member by a buffer or buffers against which the reciprocatory member abuts before it completes its amplitude of vibration in one or other direction. The buffers preferably consist of springs adjustable along the path of reciprocation and the reciprocatory member is acted upon by the spring buffer or buffers only during a fraction of its travel.

In order to avoid shocks or vibrations in the reciprocatory member during its travel, it may be desirable to provide a spring or springs adapted to act upon the reciprocatory member during the whole of its travel. The spring or springs are preferably normally under strain, either in tension or compression, so that further extension or compression of the spring will not materially affect the force exerted by the spring on the reciprocatory member.

Although in some cases it may be suffi-

cient to provide a spring on one side only of the reciprocating body, a spring may, if desired, be fitted at each side of the reciprocating body so as to more efficiently control the latter.

Figs. 7 and 8 illustrate the application of a single spring to a reciprocating hand tool adapted to be supported by a handle 43 fixed to a casing 44. The reciprocating tup 45 has lugs 46 supporting a driving spindle 47 driven by a coil spring 48 from a flexible shaft 49 and motor 50. The spindle 47 carries a spur wheel 51 driving a spur wheel 52 on a parallel spindle 53. The spindles 47 and 53 are each fitted with eccentric weights 54, the centrifugal action of which causes reciprocation of the tup 45. A spring 55 is fitted between a collar 56 on the tup 45 and a collar 57 on the casing 44. The tup 45 is adapted to strike against a tool 58 which may be a chisel, riveting hammer or the like.

In this case part of the energy stored in the tup 45 is transformed by the blow of the tool into useful work and the down-stroke is most effective when the whole of the energy is transformed. The return stroke of the tup 45 compresses the spring 55 and thus stores up energy in the spring, which is given up during the working stroke of the tup and serves to accelerate the latter. Variation of the pressure of the spring 55 or of the pressure of the tool 58 against the work by the operator, or variation of the angular velocity of the eccentric weights 54 will affect the reciprocation of the tup 45. As soon as the pressure of the tool 58 against the work drops below a certain value or the angular velocity of the eccentric weights 54 increases above a certain value the number of revolutions of the weights 54 per unit of time will be greater than the number of blows imparted by the tup 45 until only one blow takes place for every two or three revolutions of the weight 54. If the pressure on the tool is increased above a certain value, the tool will receive a blow for each revolution of the weight 54, but the latter will describe a greater or less dead angle 158 (as in Fig. 9), that is to say, the weight 54 will describe a certain angle before its centrifugal force resolves itself into a vertical component which is capable of lifting the tup 45 and overcoming the force of the spring 55.

The spring 55 is preferably normally under considerable compression so as to reduce the vibrations transmitted to the casing 44.

In order to protect the centrifugal weights 54 and driving mechanism from shocks during the stroke of the tup 45 a spring 59 may be fitted between a tup 61 and a reciprocated member 60 as in Fig. 12.

Fig. 13 illustrates a modification in which

a tup 62 is formed with a collar 63 supporting springs 64 adapted to bear against the tool 65 on the downstroke of the tup 62.

Fig. 14 illustrates a further modification in which a tup 66 strikes against a spring 70 buffer 67 on the end of the tool, anvil or the like 68.

The constructions according to Figs. 12, 13 and 14 are particularly applicable to heavy tools, such as forging hammers or pile drivers, in which case the weight of the reciprocated member or tup is equivalent to a downwardly-acting spring of constant pressure. The force of the blow will be partially stored up by the springs 59 or 64 of 80 Figs. 16 and 17 or the spring buffer 67 of Fig. 18 and accelerate the return stroke of the tup. This will be more readily understood if one considers the tup at rest when the centrifugal action of the centrifugal 85 weight or weights will lift the tup with an initial velocity to a certain height. After the downstroke the energy stored up during the blow will increase the return velocity of the tup so that it will be lifted to a 90 greater height and the force of the next blow will be correspondingly increased, thus giving a graduated increase in the height to which the tup rises, until a maximum height is reached, which will depend on the 95 ratio of the initial velocity to the added velocity due to the reaction. In such case the spring or springs absorbing a part of the blow and giving it up on the return stroke, may actually be constituted by the 100 block of steel or other body operated upon.

Fig. 10 illustrates the application of the invention to a pile. A casing 69 is mounted on the pile-driver 70 and a bottom plate 71 in the casing 69 is interposed between the 105 pile 70 and the tup 72 so that the tup strikes the pile through the medium of the plate 71. A ring 73 surrounds the upper end of the pile to prevent fracture thereof and is inclosed by an annular extension 74 and divided flange 75 which serve to hold the casing 69 in position on the driver. The tup is formed with journals supporting a cross pin 76 loosely carrying eccentric weights 77, 78 and 79. The weights are shown integral 115 with crown teeth meshing with bevel pinions 80 and 81 mounted on stub shafts 82 and 83 projecting from the cross pin 76. The pinion 80 is driven by a splined shaft 84 which is capable of sliding through a hollow shaft 85 driven from the motor 86 through a coil spring 87. By this arrangement it will be seen that the pinions 80 and 81 reciprocate with the tup 72 and that the weight 78 will revolve in the opposite direction to the weights 77 and 79 so that if the weight 78 is equal to the combined weights of 77 and 79, it will counterbalance the horizontal forces created by the weights 77 and 79. In this construction, the tup car- 130

ries a disk 88 against which bears one end of a spiral spring 89, the other end of which bears against an adjustable ring 90 externally threaded to engage a corresponding thread 91 in the casing 69. The crown of the ring 90 is formed with teeth 92 engaged by a pinion 93 rotatable from the exterior by means of a squared shaft 94 projecting through a vertical slot in the casing 69. The 10 compression of the spring 89 can thus be varied by the turning the squared shaft 94.

Fig. 11 illustrates the application of the invention to a forging hammer. In this case the mechanism is mounted on a fixed frame 15 or standard 95 having a bracket 96 which supports the motor 97 driving a splined shaft 98 through a coil spring 99. Slidable on the splined shaft 98 is a bevel pinion 100 journaled in a cross pin 101. The pinion 100 20 meshes with teeth on an eccentric weight 102 loosely rotatable on the cross pin 101. The latter is supported by lugs 103 above the tup 104 which carries a disk 105. The tup 104 is guided by collars 106 and 107 which are externally 25 in threaded engagement with an internally screwed boss 108 supported from the standard 95. The collars 106 and 107 also form abutments for springs 109 and 110 respectively and are fitted with hand wheels 30 111 and 112 for enabling the springs 110 and 111 to be adjusted in relation to the disk 105. In the position of adjustment illustrated on the drawings, the spring 110 engages the disk 105, while the spring 109 35 remains out of action. The anvil is represented by 113 supporting the work piece 114. If the distance b between the work piece 114 and the highest position of the tup 104 is less than the distance a between the disk 105 40 and spring 109, the disk 105 will not abut against the spring 109, but by adjusting the hand wheel 111 the distance a can be varied until the spring 109 is brought more or less into action. Similarly the spring 110 may 45 be lifted by the adjustment of the hand wheel 112 until the tup ceases to strike against the work piece 114. This enables the work piece to be removed, exchanged or replaced while the forging hammer continues to reciprocate.

It will be noted in Figs. 7, 10, and 11 that a coil spring is interposed between the motor and the centrifugal weights. This is in order to produce more or less uniformity in the 55 reciprocations, by absorbing the fluctuations of the motor and preventing shocks being transmitted from the reciprocating tup to the motor shaft, especially when the centrifugal weights describe the dead angle 158 referred to with reference to Fig. 9. When the centrifugal weight is describing this dead angle, the angular velocity of the weight is somewhat decreased owing to the sudden arrestment of the reciprocating tup and it is important that this sudden varia-

tion of the angular velocity of the weight should not be transmitted to the motor shaft. For this purpose the coil spring 48 (Fig. 7) 87 (Fig. 10) or 99 (Fig. 11) should have sufficient coils to be wound up to a certain 70 tension before transmitting power. By this arrangement, variations in the angular velocity of the weights would be absorbed by the coil spring and fluctuations of the motor shaft would not be transmitted to the centrifugal weights. 75

Claims:

1. Mechanism for converting rotary into reciprocatory motion, wherein continued progressive movement step-by-step in one 80 direction of the path of reciprocation is obtained, comprising a reciprocatory member, a centrifugal weight pivoted thereto, means for rotating said weight and means for impressing a unidirectional impulse upon the 85 reciprocatory member, so that it travels or progresses step-by-step in one direction.

2. Mechanism according to claim 1 having an additional centrifugal weight of equal 90 centrifugal arm length pivoted to the reciprocatory member and means for rotating the two weights in opposite directions.

3. Mechanism according to claim 1 in which the means for impressing a unidirectional impulse upon the reciprocatory member 95 comprises a buffer which may be unidirectionally progressed along the path of reciprocation.

4. Mechanism for obtaining continued progressive reciprocatory motion step-by-step in one direction from rotary motion comprising a reciprocatory member, a centrifugal weight pivoted thereto, means for rotating said weight and a spring adapted to act upon the member during the whole of 100 its travel and to impress a unidirectional impulse upon the reciprocatory member at the end of each complete vibration thereof.

5. Mechanism according to claim 4 in which the spring is normally under strain so 110 that further compression or extension of the spring will not materially affect the force exerted by the spring on the member.

6. In a reciprocatory tool, a tup, mechanism for reciprocating the tup comprising a 115 centrifugal weight pivotally mounted on the tup, means for rotating said weight and means for impressing a unidirectional impulse upon the tup at the end of each complete vibration thereof.

7. A reciprocatory tool as specified in claim 6 having a plurality of rotatable centrifugal weights of equal centrifugal arm length. 120

8. In a reciprocatory tool, a tup mechanism for reciprocating the tup comprising a centrifugal weight pivotally mounted on the tup, a casing inclosing said tup, an abutment on said casing, an abutment on the tup and a spring between said abutments. 125 130

9. A reciprocatory tool as specified in claim 8 having means for adjusting one of the abutments, so as to vary the compression of the spring.
- 5 10. In a reciprocatory tool a tup, mechanism for reciprocating the tup comprising a cross pin mounted above said tup, a revolute weight eccentrically mounted on said pin, a driving shaft, gearing splined on said 10 shaft for rotating said weight and means for rotating said shaft.
11. A reciprocatory tool comprising a driving shaft, a driven shaft, a coil spring
- interposed between said shafts, a reciprocatory tup, a centrifugal weight mounted on 15 said tup and gearing for rotating said weight from said driven shaft.
12. A reciprocatory tool comprising a tup, guides for said tup, a casing adjustably supporting said guides, a collar on said tup between said guides, springs interposed between said guides and collar, means for adjusting said guides in relation to said collar, a centrifugal weight pivotally mounted on said tup and means for rotating said weight. 20 25
